(57) **CLAIM**

The ornamental design for a welder's helmet, as shown and described.

DESCRIPTION

FIG. 1 is a perspective view of the welder's helmet;

FIG. 2 is a front view of the welder's helmet;

FIG. 3 is a back view of the welder's helmet;

FIG. 4 is a left side view of the welder's helmet;

FIG. 5 is a right side view of the welder's helmet;

FIG. 6 is a top plan view of the welder's helmet; and,

FIG. 7 is a bottom plan view of the welder's helmet.

The broken lines are included for the purpose of illustrating portions of the article and form no part of the claimed design.
